ABSTRACT

The present invention provides a method of producing small bulbs to be used in electronic equipment, particularly high-quality uniform small bulbs by a simple process, which is suitable for mass production and yields practically no rejects. The method is characterized by a large number of bulbs and bead mounts which comprise such elements as a filament, a fuse piece, a semi-conductor piece, a neon-tube electrode, or a lead switch electrode being assembled directly on a carbon plate jig with a uniform temperature distribution. The carbon plate jig is directly or indirectly heated, thereby sealing together the bulbs and the beads of the bead mounts with the jig which concurrently serves as heater.

MANUFACTURING PROCESS FOR SMALL BULBS

BACKGROUND OF THE INVENTION

It is important in the manufacture of small bulbs to assure perfect sealing of the bead of a bead mount in the bulb and to prevent leakage of any impure gas into the bulb to be sealed. For the mass production of such small bulbs it is necessary to simplify the method and work so that the work can be finished as soon as possible; the products can be uniform in quality; and the yield of rejects can be minimized. Various proposals have so far been made for manufacture of small bulbs by sealing together the bulb and the bead of a bead mount within a vacuum.

There are, however, unavoidably many technical difficulties in the manufacture of such small bulbs with outer diameter 1-6.5 mm and length 3.5-15 mm, such as assembling of bulb and bead of the bead mount to be sealed together; adsorption of generated gases; or deterioration of the vacuum due to the generated gases.

Thus every mechanical method of sealing resulted in non-uniform or inferior products and manual techniques have been the only method available, thus ruling out the possibility of mass production.

An improvement in this prior art technique is disclosed in the U.S. Pat. No. 3,698,784 by the inventor of the present invention.

This is an improvement over the conventional half-mechanized one in that it can produce superior bulbs, and 20-40 units of them at one time. But still it has too many imperfections to be used for mass production; much time is needed for setting the parts; there must be secondary treatment after the primary treatment of the product; the unnecessary portion must be cut off from the secondary treated product; precaution must be taken in positioning the bead mount within the bulb to secure uniformity of products; there is low productivity per unit area in unit time; and certain skill is required for the work.

SUMMARY OF THE INVENTION

The present invention provides a method of producing 1000 to 2000 small bulbs or even more at a time, the bulbs being uniform, of high quality with no yield of rejects in a simple mechanical operation with all the drawbacks in the above-mentioned prior art being eliminated.

To attain the intended object, in the present invention a carbon plate jig is set up in a heat-insulated box lined with metal reflector and heat shield or in a similar box enclosed within a vacuum. On said carbon plate jig are assembled a large number of bulbs and bead mounts attached with a filament, a fuse piece, a semiconductor piece, a neon-tube electrode and a lead-switch electrode. The carbon plate jig is equipped with stepped holes for positioning bulb-bead mount assemblies; and, in the case of the jig being directly heated by electric current, the jig has near both ends a large number of heat-dam holes for equalizing the temperature distribution approximately over the whole surface.

The bulb and the bead of a bead mount are to be sealed together by the heat generated from said carbon plate jig. For the purpose of heating this jig, the resistance heat generated by the direct passage of the current or the heated emitted from a quartz bulb infrared lamp or from an iodine lamp installed within the heat-insulated box is absorbed by the jig.

For the purpose of preventing impure gases from collecting in the heat-insulated box, the temperature in the heat-insulated box is progressively raised and by some appropriate means the impure gases are completely driven out of the heat-insulated box. After the heat-insulated box has been evacuated, the heat generation from the carbon plate jig is intensified in a short time, thereby sealing together the bulb and the bead of a bead mount. Lastly, the heat-insulated box is gradually cooled and with an atmospheric pressure restored therein, the final products, i.e., finished small bulbs are taken out of the box.

BRIEF DESCRIPTION OF THE DRAWINGS

The manufacturing process of small bulbs according to the present invention will become apparent by reading the following detailed account in conjunction with the attached drawings.

In the attached drawings, FIG. 1 illustrates one embodiment of the device for manufacturing small bulbs in accordance with the process of the present invention.

FIG. 2 shows the embodiment of FIG. 1 in greater detail with a partial section.

FIG. 3 is a plan view of the main body of the heat-insulated box and a partially cut away carbon plate jig in FIG. 2.

FIG. 4 is a partial enlargement of the carbon plate jig in FIG. 2.

FIG. 5 illustrates another embodiment of the device for manufacturing small bulbs in accordance with the process of the present invention.

FIG. 6 shows the embodiment of FIG. 5 in greater detail with a partial section.

FIG. 7 is a plan view of the main body of the heat-insulated box and a partially cutaway carbon plate jig in FIG. 6.

FIG. 8 is a partial enlargement of the carbon plate jig in FIG. 6.

FIG. 9 is a sectional view of a finished bulb.

DESCRIPTION OF THE PREFERRED EMBODIMENTS

An example of the device for manufacturing small bulbs in accordance with the present invention is to be described referring to the corresponding drawings. In all the drawings, same symbols represent same parts.

In FIGS. 1, 2, 3, 4 and 9, a bead 3 is mounted on a pair of lead wires 1 and 2 separated by a specified gap. Between the tops of said wires 1 and 2 is stretched a filament 4, thus completing a bead mount A.

Next, a bead mount A with the filament 4 on the upper side is, fitted into each step 6a of a plurality of stepped holes 6. The holes 6 are provided on a rectangular carbon plate jig 5; and from above, a bulb 7 of a specified size with its top closed and its bottom open is fitted to the step 6a so as to embrace the bead 3 of the bead mount A. Thus the assembling by positioning the bulb 7 and the bead mount A is completed. The carbon plate jig 5 thus assembled is placed above the main body 9 of the heat-insulated box set on the stand 8 within the vacuum box B, with the electrode junction holes 10 at both ends holding the electrodes 11 in such a manner that said jig may not come into contact with said main body 9. The cover 13 for the heat-insulated box has a notched hole 12 so bored as not to touch the

carbon plate jig 5 is put on the top of the main body 9 of the heat-insulated box.

Next, the heaters for supplemental heating 14 and 15 fixed to both sides of the main body 9 and the cover 13 of the heat-insulated box are separately connected. The cap terminals at their ends 17, 18, 19 and 20 are connected to the electrodes 16 separately provided.

The whole structure is then covered; the lid 21 is put on the vacuum box B; and the electrodes 11 and 16 jutting out from the base 22 of the vacuum box B through the insulators 23 and 24 are connected to the appropriate power sources. Suction is used through the vent hole 25 provided on the base 22, the vacuum box B and the heat-insulated box 9 and 13 are evacuated and the sucking state continues to be maintained.

In this state the power supply to the heaters for supplemental heating 14 and 15 is switched ON to heat up the heat-insulated box 9 and 13 from both sides. Then the power supply to the carbon plate jig 5 is switched ON to maintain a constant temperature of, say, 500°C which accelerates the generation of impure gases out of the metal parts inside the heat-insulated box 9 and 13. When within the heat-insulated box 9 and 13 impure gases are generated in sufficient quantities and they are expelled out of the vacuum box B, the power supplied to the carbon plate jig 5 is increased to raise the temperature in the heat-insulated box 9 and 13 to nearly the glass-softening point, say, to 550°C, thereby to induce possible generation of more of impure gases. These gases are driven out of the vacuum box B. After complete removal of the impure gases generated in the heat-insulated box 9 and 13 from the vacuum box B, the power supplied to the carbon plate jig 5 is further increased to raise the temperature of the carbon plate jig 5 up to the glass-melting point of, say, 600°C in a short time, thereby sealing together the bulb 7 and the bead 3 of the bead mount A.

Subsequently the power supply to the heaters for supplemental heating 14 and 15 and to the carbon plate jig 5 is turned OFF and the condition is left as it is for a brief time, or the heat-insulated box 9 and 13 is gradually cooled by introducing nitrogen gas into the vacuum box B and the heat-insulated box 9 and 13 through the vent hole 25.

After this cooling, the air is admitted into the vacuum box B through said hole 25, thereby restoring the atmospheric pressure therein. The lid 21 of the vacuum box B is taken off the base 22; the cap terminals 18 and 20 are disconnected from the electrodes 16; and the cover 13 of the heat-insulated box is taken off the main body of said box. Then the carbon plate jig 5 is unfastened from the electrodes 11; and a finished product, i.e. a small bulb C with the bulb 7 and the bead 3 of the bead mount A sealed together, is taken out, thus completing the whole process.

In this embodiment of manufacturing small bulbs, however, a few problems arise. One is a problem of electrical characteristic that when the current flows in the carbon plate jig 5, the heat is generated from the central portion due to the resistance; and thus even when the glass-melting point is attained at the central portion, both sides of it are still below of the glass-melting point. Thus, the end portions of the carbon plate jig 5 cannot be as hot as the central portion, because of the electrical resistance and the escape of heat to the electrode junctions. For this reason, even if the parts-fitting holes 6 are provided practically all over the

surface of the carbon jig 5, not all of the products will be of uniform quality and accordingly the area assuring uniformity of products is limited to the central portion. Therefore, the method may be more mass-productive than the conventional one, but the mass-productivity realized will not be as great as expected from the present invention as one of its objects. This problem has however been solved as follows: at both ends of the carbon plate jig a large number of tiny holes 26 are bored and the current from per unit area of these portions is enriched, while the heat dissipation toward both ends in heated carbon plate jig 5 is prevented by the electrical resistance which has been made as high as possible, thereby widening the extent of equalized temperature distribution in the carbon plate jig 5 itself. Both sides of the main body 9 and the cover 13 of the heat-insulated box are provided with the supplemental heaters 14 and 15 to compensate for the loss of heat to both ends of the carbon plate jig 5, the supplemental heaters being composed of common resistance heaters wherein a nichrome wire penetrates a quartz glass tube.

The heat-insulated box 9 and 13 is lined with heat-insulating, heat-resistant sintered plates 27 and with one or more mirror-finished heat-resistant reflectors 28 of such metal as molybdenum or stainless steel which is least likely to emit metal gases. This enables intensifying the temperature rise on the carbon plate jig in the heat-insulated box 9 and 13 and suppressing the temperature rise outside of the heat-insulated box 9 and 13.

On the bottom of the main body 9 of the heat-insulated box there are mounted, on both sides of the central portion, mirror-finished split metal reflectors 29 of molybdenum or stainless steel respectively with a reflecting inclination between a set of supports 30. The heat of the central portion can thereby be reflected in both directions to improve the uniformity of temperature distribution within the heat-insulated box 9 and 13.

According to this method, the temperature distribution within the heat-insulated box 9 and 13 and the temperature distribution of the carbon plate jig 5 over a wide area extending from the center of the jig to the proximate ends thereof, can be equalized and it becomes possible to manufacture uniform products in great quantities at a time.

For instance, it has been experimentally confirmed that all the products will be uniform in quality, even when small bulbs are produced using 1029 holes 6 of 3.2 mm diameter provided on a rectangular carbon plate jig 5 measuring 35 cm long and 10 cm wide.

In the drawings the sintered plate 27 and the metal reflector 28 are set with an adequate fine gap between them. The main body 9 and the cover 13 of the heat-insulated box are fixed by means of a metal clamp 31. An airtight rubber ring 32 is fitted into the groove 33 cut on the base 22 of the vacuum box B, thereby sealing the lid 21 of the vacuum box B airtight with the base 22.

Another problem is raised by degradation of the product quality through infiltration into the bulb of the impure gases such as metal gases which are generated from the heaters or from outside and inside of the heat-insulated box.

Generally in the manufacture of such small bulbs, emission of impure gases from the metal parts of the

device is unavoidable, because the device itself is exposed to high temperatures.

For this reason when the bulb and the bead of a bead mount are sealed together, impure gases are entrapped within the bulb, resulting in poor evacuation or rejection of the product on account of being tainted through gas adsorption.

In the present embodiment, the problem has been solved as follows. The jig 5 for assembling the bulb 7 and the bead mount A is fabricated of carbon and the jig 5 itself is heated for sealing them, thereby eliminating the possibility of impure gases being generated from the heater itself.

The heat-resistant reflector 28 which lines the heat-insulated box 9 and 13 is made of a mirror-finished heat-resistant metal such as molybdenum or stainless steel, thereby minimizing the emission of impure gases.

The inside walls of the heat-insulated box 9 and 13 include a sintered heat-resistant plate 27 and thereby the outside surface of the heat-insulated box and the objects outside of it can be kept as cold as possible, so that a metal gas-emitting temperature may not be attained.

The heating conditions are such that at first the temperature of the heat-insulated box 9 and 13 including the carbon plate jig 5 is elevated to, say, 500°C. This temperature is maintained for some time to induce gas emission from the objects inside of the box. The emitted gas is exhausted through the vent hole 34 provided at mid-bottom of the main body 9 of the heat-insulated box and through the vent hole 25 of the vacuum box B, thereby equalizing the atmospheric conditions within the heat-insulated box 9 and 13. Next, the temperature is brought up close to the glass-melting point and the gas exhaustion is continued. Following the complete elimination of gas, the temperature is raised to the glass-melting point in a brief time, thereby sealing together the bulb 7 and the bead 3 of a bead mount A.

According to this method, the yield of impure gases in the heat-insulated box 9 and 13 is extremely low; and the impure gases generated outside of the box as well as inside of it can be thoroughly driven out before the sealing of bulb and bead, because the exhaustion of gas is continuous while the temperature within the heat-insulated box 9 and 13 is being progressively increased. Thus the leakage of impure gas into the bulb 7 can be prevented.

The sintered plate 27 and the metal reflector 28 which cover the bottom of the main body 9 of the heat-insulated box are bored with a large number of tiny holes 35 located in a staggered fashion for better reflectivity. The impure gases generated in the heat-insulated box 9 and 13 can be expelled through these tiny holes and then through the vent hole 25 in the bottom of the main body 9 of the heat-insulated box.

Another embodiment of the present invention is to be described referring to FIGS. 5, 6, 7, 8 and 9. The method is the same as in the first embodiment except that in the second embodiment, the carbon plate jig is heated by infrared rays and the heat absorbed by the carbon plate jig seals together the bulb 7 and the bead 3 of a bead mount A. The infrared reflection box has the same structure as the heat-insulated box but is not enclosed in a vacuum box B.

The manufacturing process of small bulbs C in the second example is to be described referring to FIGS.

5-9. In these figures and in those for the first example, same symbols denote the same parts.

At first, in the same manner as in the first embodiment, bulbs 7 and bead mounts A are assembled on the steps 6a of numerous stepped holes 6 for positioning, which are provided on a rectangular carbon plate jig 38, which is small enough to go into the infrared reflection box 36 and 37. These assemblies are placed on the sintered heat-resistant plate 27 at the top of the main body 36 of the infrared reflection box and the lid 37 of the infrared reflection box with a flange 42 which closely fits the top fringe groove 41 of the main body 36 of the infrared reflection box is placed on top.

Then the terminals of nine infrared heaters consisting of quartz tube infrared lamps or iodine lamps installed within the main body 36 of the infrared reflection box installed on the stand 40 of the foundation 39 are coupled to conductive bars 44 and 45; and the terminals of said conductive bars 44 and 45. The cap terminals 46 and 47 are attached to the terminals of the conductive bars 44 and 45 projecting through vacuum lead terminals of the prior art out of the main body 36 of the infrared reflection box and are connected to the electrodes 50 and 51 fitted through the insulators 48 and 49 to the foundation 39.

Next the bottom ends of said electrodes 50 and 51 are connected to the power supply. Then using the common method of suction, the infrared reflection box 36 and 37 is evacuated through the vent hole 34 at about mid-bottom of the main body 36 of the infrared reflection box and through the vent pipe 52 penetrating the foundation 39. The suction is continuous. In this state the power supply to the infrared heater 43 is turned ON and the heating is continued until the impure gas-emitting temperature, say, 500°C is reached on the metal parts within the infrared reflection box 36 and 37.

In the meantime, the carbon plate jig 38 becomes steadily hotter than the infrared reflection box 36, 37, on account of its heat absorption characteristic, absorbing the heat from the infrared heater 43 and receiving the heat reflected from the metal reflector 28 similar to the first embodiment and from a split metal reflector 29. In two minutes after the temperature in the infrared reflection box 36 and 37 has reached 600°C, the temperature of the carbon plate jig 38 reaches the glass-melting point, as experimentally confirmed.

Accordingly in about two minutes of this temperature being attained in the infrared reflection box 36 and 37, the sealing of the bulb 7 and the bead mount A is completed. Immediately after passage of this time the power supply to the infrared heater 43 is cut off; and the infrared reflection box 36 and 37 is gradually cooled by introducing nitrogen gas therein through the vent pipe 52. When the cooling is finished, the air is admitted through the vent pipe 52 into the infrared reflection box 36 and 37 to restore the atmospheric pressure therein and the lid 37 is taken off the main body 36.

Then the carbon plate jig 38 is taken out of the main body 36 of the infrared reflection box and from said jig 38 finished products, i.e., small bulbs C with sealed assemblies of bulb 7 and bead 3 of bead mount A are obtained, thus completing the whole process.

In this embodiment, unlike in the first embodiment, the infrared reflection box 36 and 37 is not placed in a vacuum box B, but the object of the present invention

will be accomplished all the same whether such a vacuum box B is used or not.

Meanwhile, known means of prior art can be adequately selected for airtight fitting of the main body 36 and the lid 37 of the infrared reflection box; for providing the infrared heaters 43; for limiting the ignition of said infrared heaters 43 before the bulb-bead sealing temperature is reached and then igniting all of the heaters to attain the sealing temperature; or for controlling the temperature of the carbon plate jig.

When in accordance with the method of this embodiment 1029 sets of bulbs 7 measuring 3.2 mm in diameter were assembled on a rectangular carbon plate jig 38 of 18 cm length and 10 cm width and the sealing of bulb 7 and bead mount A was executed using 12 100V, 500W infrared lamps, all of the 1029 small bulbs C obtained turned out satisfactory with a perfect seal, regardless of the positions where they were fitted on the carbon plate jig 38.

In the first and second embodiments, the degree of vacuum in the vacuum box B, the heat-insulated box 9 and 13 and the infrared reflection box 36 and 37; the temperature of the heater; and the heating duration may vary depending on the size and wall thickness of small bulbs to be produced or on the bead of the bead mount, but these conditions can be appropriately set by the known technical means.

In the described embodiments, an increase in dimensions of the device for a more efficient mass production of bulbs or selection of apparatus for execution of the present invention are obvious modifications.

As described above the present invention is characterized in that the device is simple, calling for no skill for its operation. The products are of equal quality with no variation, because the bulb and the bead mount can be properly set by merely attaching them to the steps of the parts-fitting holes provided on the carbon plate jig, and thereby the bead mount can be exactly centered relative to the bulb.

Furthermore, the carbon plate jig, which serves for both assembling the bulb and the bead mount and heating to seal them together, can minimize the generation of impure gases like metal gass as compared with a metallic jig. On the other hand, in the present invention the gas-emitting temperature is maintained for some time; and the impure gases generated in that time are driven out before the sealing of bulb and bead mount takes place. As the result a product of high quality with no

impure gas left in the bulb can be produced.

Further, the invented process involves few steps and the sealing of bulb and bulb mount can be simply executed. In consequence no rejects are produced and this contributes to cost reduction of production.

The present invention may be embodied in other specific forms without departing from the spirit or essential characteristics thereof. The presently disclosed embodiments are therefore to be considered in all respects 10 as illustrative and not restrictive, the scope of the invention being indicated by the appended claims rather than the foregoing description, and all changes which come within the meaning and range of equivalency of the claims are therefore intended to be embraced therein.

What is claimed is:

1. A method of making small bulbs by fusing bead mounts with elements therein to a bulb envelope comprising:
  - a. inserting a plurality of said bead mounts into a plurality of holes in a carbon jig plate;
  - b. placing a bulb envelope in contact with each of said bead mounts;
  - c. placing said carbon jig plate with the plurality of unsealed bulbs assembled thereon within a heat insulated box;
  - d. evacuating said heat insulated box;
  - e. heating said carbon jig plate to a temperature for inducing the generation of impure gases and withdrawing said impure gases, further raising the temperature to a value close to the softening point of said bulb envelopes and then further heating said carbon jig plate to a temperature sufficient to cause the fusing of said bead mounts and said bulb envelopes; and
  - f. gradually cooling the inside of said heat insulated box.
2. The method of claim 1 wherein heating said carbon plate jig includes passing an electric current through said carbon plate jig and thereby generating heat due to the resistance thereof.
3. The method of claim 1 wherein heating said carbon plate jig includes exposing said carbon plate jig to infrared radiation.
4. The method of claim 1, wherein heating said carbon plate jig includes internally reflecting the heat in said box means back to said carbon plate jig.
